UNITED STATES PATENT OFFICE.

JOHN SCHAEFFER, OF HORICON, WISCONSIN, ASSIGNOR TO VAN BRUNT MANUFACTURING COMPANY, OF HORICON, WISCONSIN, A CORPORATION OF WISCONSIN.

LATCH DEVICE.

1,333,684.

Specification of Letters Patent. Patented Mar. 16, 1920.

Application filed July 21, 1919. Serial No. 312,396.

To all whom it may concern:

Be it known that I, JOHN SCHAEFFER, a citizen of the United States, and a resident of Horicon, in the county of Dodge and 5 State of Wisconsin, have invented certain new and useful Improvements in Latch Devices, of which the following is a specification, reference being had to the accompanying drawings.

10 This invention relates to a latch device designed primarily for withdrawing and holding out of operative engagement one of the elements of a gear mechanism, and it has for its object to so construct the latch that 15 a pull thereon will cause it to be moved so that it will positively hold in retracted or inoperative position the member with which it is connected, and will so remain until a further movement in the same direction of 20 the latch-operating means will cause its release and permit the return of said attached member to operative position. This object I accomplish as illustrated in the drawings and hereinafter described—the illustration 25 and the description being in connection with the use of the invention as embodied in a well-known type of grain-drill. What I believe to be new will be set forth in the claims.

30 In the drawings,

Figure 1 is an end view of the long seed-box of a grain-drill and the gearing connected therewith through which the feeding of the grain from the box is compelled, and 35 showing my improvements applied to the rear of said seed-box;

Fig. 2 is a rear view of the seed-box and the other parts shown in Fig. 1, the seed-box being partly broken away, and my improvements being shown applied to the rear 40 wall of said box adjacent each end thereof;

Fig. 3 is a detail, being a vertical section at line 3—3 of Fig. 2 and showing the gearing through which the seed-delivering mechanism is actuated by the rotation of the 45 main axle of the machine;

Fig. 4 is an enlarged detail of my improved latching device, the front plate or cover of the casing being removed, and 50 showing the movable bar member locked in its raised or retracted position;

Fig. 5 is a view like Fig. 4, but with the movable bar member in its unlocked or lowermost position;

55 Fig. 6 is a rear view of the casing in

which is movably mounted the latch bar, the view also showing the bar-actuating lever and the spring that is slidingly connected with the bar; and

Fig. 7 is a detail, showing the spring that 60 bears against the movable arm member to hold it in either of its adjusted positions.

Referring to the several figures of the drawings,—10 indicates the long hopper-like seed-box of an ordinary grain-drill. 11 indicates a shaft below the hopper and upon which are mounted in the usual manner the feeding mechanisms as usual. 12 indicates the main axle of the machine. 13 indicates a spur gear fast upon the axle 12 and in 65 mesh with a gear 14 that in turn meshes with a gear 15 fast upon the drill shaft 11. By means of such gearing the drill shaft 11 will be rotated upon the forward motion of the machine, as will be understood. It has 70 been customary to support the gear 14 in a frame secured to the shaft 11 and to raise such frame sufficiently to draw the gear 14 out of mesh with the gear 13 so as to stop the operation of the seeding mechanism. I 75 retain this same method of movably supporting the gear 14, and, as best shown in Fig. 3, the frame referred to is shown and indicated by 16, and, as there shown, such frame partly surrounds the gear 14—the 80 gear being journaled therein at 17 as shown. Under normal working conditions this gear-carrying frame is held forced down so as to compel a constant engagement of the gear 14 with the gear on the main axle, such forcing 85 down being by means of a strong coiled spring 18 interposed between the frame and a bracket 19 secured to the rear face of the seed-box.

My improved invention has, in its present 90 application, to do with improved means for raising the gear 14 out of mesh with the driving gear on the axle, and is so constructed and applied that it can be operated by the driver at any time while the machine 95 is in motion and without the driver having to leave his seat. A set of gearing such as described is ordinarily used at each end of one of these grain-drills, and, as shown in Fig. 2, one of my improved latch devices is 100 used in connection with each set of such gearing, and the two latches are so connected up to a common actuating device that they will be actuated simultaneously. Inasmuch, however, as the latch at each end and 110

the parts connected immediately therewith are the same, a description of the devices at one end of the seed-box will be sufficient.

20 indicates a casing preferably made as 5 a single casting with the exception of its front or cover plate 21, which, as indicated in Fig. 2, will be bolted to the body portion 20. The body portion 20 of the casing has 10 projecting from its rear side lugs 22 through which bolts will be passed to attach it properly in place to the rear wall of the seed-box. The chamber of the casing member 20 is very considerably wider at its upper 15 end than at its lower end, as clearly shown in Figs. 4 and 5, one of the side walls of the said chamber being shown as curved, and in the upper part of the chamber there is located a block 23 which is preferably formed integral with the casing member 20 and 20 which is located so as to leave a space or passageway between it and the walls of the chamber. One of the side or edge walls of the chamber is indicated by 24, and the other by 25, the latter being shown as very decidedly 25 curved so as to bring its lower end quite close to the lower end of the wall 24. The upper wall portion of the chamber is shaped, in the construction shown, to provide two recesses 26 and 27, and the latter recess, it will be noted, extends up somewhat higher in the casing than does the recess 26. The walls of these recesses 26 and 27 are curved to approximately semi-circles and the two recesses are separated by a 30 downwardly-extending projection 28, the edges of which are curved. The projection 28 projects substantially opposite the center portion of the upper edge of the block 23 and such upper edge is quite deeply curved 35 in such manner so as to form, in connection with the downward projection 28, a curved passageway 29 that connects the two recesses 26-27—the upper ends of the block 23 extending into the said recesses, as shown. 40 45 50 55 60 65 70 75 80 85 90 95 100 105 110 115 120 125 130

30 indicates a bar, here shown as formed of a strip of plate metal, which carries at its lower end a stud 31 that projects toward the inner face of the chamber and is of a size and shape to adapt it to travel freely through the spaces at each side of the block 23 and through the connecting passage 29—its length being such as to allow the inner face of the bar 30 to move in contact, or nearly so, with the block 23, the outer face 55 of which block will ordinarily be flush with the outer face of the casing. The cover 21 of the casing will be provided with side flanges so that the body of the cover when in place will lie close to the outer face of the bar 30 so as to hold such bar movably in place in the casing. The upper marginal portion of the cover plate 21 will not be flanged, of course, and thus the bar is allowed to project from the casing and be 60 moved freely up and down, as hereinafter

described. Rising from the upper end of the casing body 20, and preferably cast therewith, is a bracket 32, to the upper end of which is pivotally attached by a pivot bolt 33 a bent lever 34, the bracket being 70 preferably bifurcated and the bent lever located in such bifurcation. The outer end of the shorter arm of the bent lever is pivotally connected to the arm 30 at a short distance below the upper end of such arm, the 75 pivot being indicated by 35. At the end of the longer arm of the bent lever I have shown an eye, indicated by 36, to which to attach a rope that leads to a point convenient to the operator of the machine. 37 and 38 80 indicate the two arms of a spring, an intermediate portion of which, indicated by 39, is coiled, and, as shown in Fig. 6, is placed around the inner end of the pivot bolt 33 and suitably secured thereon by a washer, which 85 washer may be held in place by upsetting the end of the bolt against it or by a nut secured on the bolt. One end of this spring—the longer one in the construction shown—is extended down and held against a stud 90 on the face of the casing while the other end extends forward and has a sliding connection with the upper end of the arm 30—the connection of this spring arm with the arm 30 being effected, in the construction 95 shown, by passing the spring arm 38 loosely through a transverse opening in a short stud 40 that is rotatably mounted in the upper end of the arm 30. 41 indicates a link, the upper end of which is turned to adapt it to 100 hook into a hole 42 formed in the short arm of the bent lever 34 and having another hook at its lower end to adapt it to connect with a loop 43 or other device carried by the movable frame 16 in which the gear 14 is journaled. 44 is a rope made fast in the eye 36 of the bent lever 34, and, as shown in Fig. 2, the ropes 44 leading from the devices at the opposite ends of the seed-box pass through an eye 45 rigidly affixed to a 110 central portion of the upper part of the seed-box, and both of them lead to a point within convenient reach of the operator, and, if desired, may, after passing through the said eye 45, be connected together or to 115 a common shifting device so that at one operation both of the bent levers 34 will be operated simultaneously.

With the latch mechanism in the position indicated in Fig. 5 and with the gear frame 120 16 connected with the bent lever 34 through the medium of the link 41, the various gears through which the seeding mechanism is driven will be in mesh as in Fig. 1. Now, when it is desired to stop the seeding operation the driver will, by a pull on the rope 44, turn the bent lever 34 on its pivot 33 and in doing that he will cause such lever to turn as far as possible. The movement of the lever backward on its pivot will 125 130

be stopped by reason of the stud 31 at the lower end of the arm 30 coming in contact with the upper part of the curved edge of the recess 26. Upon the lever being thus 5 stopped the operator will release the pull, and thereupon, under the influence of the spring that is coiled around the pivot bolt 33 and that has one of its arms slidingly 10 engaging the stud 40 at the upper end of the arm 30, such arm will be forced not only downward but it will be turned on its pivot 35 to swing the part below the pivot toward the left as seen in Fig. 4. The stud 31 will by contact with the curved edge of the projection 28 be directed into the passage 29 and against the curved upper edge of the block 23 where it will be brought to rest, as 15 shown in Fig. 4. The downward pressure of the spring arm 38 will hold it firmly 20 against the block and thus, of course, hold the gear 14 raised and out of mesh with the driving gear 13 due to the connection, by means of the link 41, of the gear frame 16 with the short arm of the bent lever 34. 25 To release the locking engagement of the arm 30 with the block 23 the operator will give another pull upon the rope to turn the bent lever in the same direction that it was turned to effect a raising of the arm to locking 30 position, and this second pull upon the lever will cause the stud 31 to ride up alongside of the opposite curved edge of the projection 28 and abut against the curved edge 35 wall of the recess 27, and upon the release of the pull on the lever the said spring will force the arm 30 downward with the stud 31 traveling against the curved outer edge 25. Such downward movement brings the parts into the position shown in Fig. 5, 40 and, of course, also carries down the gear frame 16 so as to bring the gear 14 carried thereby again into operative relation with the drive gear 13.

By reason of the sliding engagement of the 45 spring arm 38 with the bar 30 above the point of pivotal attachment of such bar with the operating lever 34 it will be seen that during the first part of the longitudinal movement of the bar to carry its lower end 50 toward the upper part of the chamber the pressure of the spring will be exerted in substantially a downward direction,—that is will oppose the longitudinal movement of the bar with but very little tendency to 55 cause it to swing on its pivot. As the stud 31 enters the space between the upper part of the block 23 and the adjacent side wall 24 the inner end of the bar will, of course, turn inward and thereupon the spring will 60 tend to force such inner end of the bar toward and against the side of the block, the result being that as the stud 31 enters the recess 26 the spring will so turn the bar as to move the stud against the side of the projection 28, and, upon the release of the pull 65

on the lever, the stud will, by reason of the spring pressure, be guided down by the projection 28 against the curved or recessed upper edge of the block 23 and there held until the next pull on the lever causes its 70 disengagement and its entry into the recess 27, as before stated.

By my invention I provide a latching device of very simple construction which is capable of being operated by a single stroke 75 of a lever or other device that will cause a raising and locking of the latch bar and which can only be released from locking position by a short stroke of the same lever or other device in the same direction. 80

What I claim as my invention and desire to secure by Letters Patent, is—

1. A device of the class described, comprising in combination a casing, a bar longitudinally movable therein and projecting 85 therefrom at one end, a stop in and near one end of said casing, and means connected with said bar and adapted by successive movements in the same direction to move the bar into position to be first engaged by said 90 stop and then be released therefrom.

2. A device of the class described, comprising in combination a casing, a pivoted bar longitudinally and laterally movable therein and projecting therefrom at one end, 95 a stop in and near one end of said casing, a spring for causing the bar to move laterally and for holding it in engagement with said stop, and means connected with said bar and adapted by successive movements in the 100 same direction to longitudinally move said bar to first bring its inner end into position to be engaged with said stop and then moving it away from said stop.

3. A device of the class described, comprising in combination a casing, a pivoted bar longitudinally and laterally movable therein and projecting therefrom at one end, a stud on one face of the bar adjacent its inner end, 110 a stop in and near one end of said casing and standing at a distance from the edge walls of the chamber of the casing to form a guiding passage for the said stud, a spring for causing the bar to move laterally and for holding said stud in engagement with said 115 stop, and means connected with said bar and adapted by successive movements in the same direction to longitudinally move the bar to permit said stud to engage said stop and then disengage it from the stop and move it 120 away therefrom.

4. A device of the class described, comprising in combination a casing, a bar longitudinally and laterally movable therein and projecting therefrom at one end, a stop in said casing with which said bar is adapted to engage, means movable in one direction for longitudinally moving said arm to bring its inner end portion into position to engage said stop and thereafter movable in the same 130

direction for releasing said bar from said stop, and means for compelling the inner end of said arm to move laterally over and away from said stop.

5. A device of the class described, comprising in combination a casing, a bar longitudinally and laterally movable therein and projecting therefrom at one end, a stop in said casing with which said bar is adapted 10 to engage, means movable in one direction for longitudinally moving said arm to bring its inner end portion into position to engage said stop and thereafter movable in the same direction for releasing said bar 15 from said stop, and resilient means for compelling the inner end of said arm to move laterally over and away from said stop.

6. A device of the class described, comprising in combination a casing, a bar longitudinally and laterally movable therein and projecting therefrom at one end, a stop in said casing with which said bar is adapted 20 to engage, means movable in one direction for longitudinally moving said arm to bring its inner end portion into position to engage said stop and thereafter movable in the same direction for releasing said bar from said stop, and a spring connected with said bar for opposing its longitudinal movement in 25 one direction and for compelling a lateral movement of the arm when said arm is moved into and out of engagement with said stop.

7. A device of the class described, comprising in combination a casing, a bar longitudinally and laterally movable therein and projecting therefrom at one end, a stop in said casing, means for moving said bar longitudinally in one direction between the 30 stop and one of the side walls of the chamber of the casing and by a succeeding movement of said means in the same direction permitting a reverse movement of the arm between the stop and the other side wall 35 of said chamber, and a spring device acting upon said bar for causing an engagement of the bar with the stop between successive operations of said bar-moving means.

8. A device of the class described, comprising in combination a casing, a bar longitudinally and laterally movable therein and projecting therefrom at one end, a stop in said casing having a recessed upper edge, a stud on one face of said bar adapted to 50 rest on said recessed upper edge, means for moving said bar longitudinally in one direction and by a succeeding movement of said means in the same direction permitting a reverse movement of the bar, and a spring 55 device acting upon said arm for causing an engagement of the stud with said bar between the successive operations of said bar-moving means.

9. A device of the class described, com-

prising in combination a casing, a bar longitudinally and laterally movable therein and projecting therefrom at one end, a stud extending from one face of and near the inner end of said bar, a stop in the chamber of said casing near one end thereof, said stop 65 having a recess in its upper edge and the upper wall of the chamber having a projection extending downward toward said recessed edge, means for moving said bar longitudinally in one direction along one 70 side of said stop to bring said stud into proximity to said downwardly-extending projection and by a succeeding movement of said means in the same direction permitting a reverse movement of the bar at the 75 other side of said stop, and a spring device acting upon said bar for causing an engagement of the stud with the recessed edge of the stop between successive operations of the 80 said bar-moving means, said downwardly-extending projection acting to guide said stud toward and away from said stop.

10. A device of the class described, comprising in combination a casing, a bar longitudinally movable therein and having one 90 end projecting therefrom, a stop in and near one end of said casing, a lever pivoted upon a fixed support and also pivotally connected to the projecting portion of said bar, a stud adjacent the inner end of the 95 bar for engaging said stop when said bar is moved longitudinally in one direction by a stroke of the lever, and a spring connected with said arm to turn it at the conclusion of said longitudinal movement and 100 force it into engagement with the stop, said spring upon the next succeeding stroke of the lever in the same direction carrying said stud past and free from said stop.

11. A device of the class described, comprising in combination a casing, a bar longitudinally movable therein and having one end projecting therefrom, a stop in and near one end of said casing, a lever pivoted upon a fixed support and also pivotally connected to the projecting portion of said bar at a distance from the outer end thereof, a stud adjacent the inner end of the bar for engaging said stop when said bar is moved longitudinally in one direction by a stroke 115 of the lever, and a spring carried by a fixed support at one side of said arm and slidably engaging said arm above the point of pivotal connection of the arm with the lever, said spring acting to turn said bar 120 at the conclusion of said longitudinal movement to force the stud on said bar into engagement with said stop and upon the next succeeding stroke of the lever in the same direction carrying said stud past and free 125 from said stop.

JOHN SCHAEFFER.
